UNITED STATES PATENT OFFICE

EUGENE D. MERWIN, OF SEATTLE, WASHINGTON.

APPARATUS FOR GRADING AND WASHING HEAVY MATERIAL.

Application filed February 24, 1921. Serial No. 447,401.

To all whom it may concern:

Be it known that I, EUGENE D. MERWIN, a citizen of the United States, residing at Seattle, in the county of King and State of Washington, have invented a certain new and useful Improvement in Apparatus for Grading and Washing Heavy Material, of which the following is a specification.

My invention relates to improvements in apparatus for grading and washing materials that have a greater specific gravity than water and is in the nature of an improvement on the grading and washing apparatus disclosed in my prior application, Serial No. 358,899, filed February 16th, 1920.

The object of my improvement is to provide apparatus wherein the grading of materials with respect to size and specific gravity will be accomplished by permitting them to settle through a current of water that is flowing at substantially right angles to the direction of movement of the particles of material.

Another object is to provide apparatus of this nature including a grader box of substantially V-shaped cross section having at its forward end a plurality of horizontal slots arranged one above another and communicating with an externally disposed pressure tank whereby a plurality of horizontal sheets of water will be discharged into the inlet end of the grader box.

A further object is to provide apparatus of this nature having at its inlet end a pressure box for water that is divided into an upper and lower compartment and to further provide a vertically adjustable pressure tank that is connected with the lower compartment of the pressure box so that water may be introduced at higher pressure in the lower portion of the grader box than it is in the upper portion of such grader box, the water that is introduced in the lower compartment being always fresh, clean water while the water that is introduced into the upper compartment being, in some instances, water that has already been used.

A further object is to provide mechanism for deriving power from material and water that are delivered from a higher elevation to the machine, which power is used for operating certain parts of the machine.

A still further object is to provide novel and efficient valve mechanism for drawing

off the graded material from the bottom of the grader box, said valve mechanism being practically free from friction and wear.

With the above and other objects in view as will appear from the following description, the invention consists in the novel construction, adaptation and combination of parts of a grading and washing machine as will be more clearly hereinafter described and claimed.

In the drawings, Figure 1 is a view in vertical section substantially on the longitudinal medial plane of a grading and washing apparatus constructed in accordance with my invention. Fig. 2 is a sectional view substantially on the broken line 2, 2 of Fig. 1, certain parts being shown in elevation. Fig. 3 is an enlarged view partly in cross section and partly in elevation showing parts of the valve mechanism by which the material is removed from the bottom of the grader box. Fig. 4 is a sectional view of a rotary screen substantially on a broken line 4, 4 of Fig. 1. Fig. 5 is an enlarged fragmentary sectional view substantially on a broken line 5, 5 of Fig. 2. Fig. 6 is a view in perspective of a cross bar that is used on the top of the grader box and Fig. 7 is a view in elevation with parts broken away, of an overshot water wheel.

Like reference numerals designate like parts throughout the several views.

Referring to the drawings, I have shown a substantially V-shaped grader box comprising two downwardly convergent side members 10 that are provided with end plates 11 and 12 at the inlet and discharge ends of the grader box respectively and that are further provided with a bottom plate 20 having perforations or valve openings 21 at regular intervals through which material may be drawn off.

The grader box may be supported within a suitably designed frame 13 which is preferably constructed of channel and angle bars.

The grader box is provided at its forward end with an externally disposed water receptacle or pressure box 14 that preferably converges toward the lower end as shown in Fig. 1 and that is divided into an upper and a lower compartment by a horizontal partition 15. The partition 15 is preferably provided with a perforation 16 that may be opened and closed by a slide 17 which is

secured to and may be operated by a rod 18 that projects outwardly through the side of the pressure box.

The bottom 20 of the grader box is held securely in contact with the side plates 10 by vertical tie rods 22 whose ends project through perforations 23 in bars 24 that extend across the top of the box. The bars 24 are preferably provided near each end with a plurality of perforations 23 as shown in Fig. 6 so that the width of the top of the grader box may be varied. The end plates 11 and 12 are held tightly in contact with the ends of the side plates 10 by longitudinally arranged tie rods 25.

Packing strips 26 are preferably provided between the side plates 10 and the end plates 11 and 12 and bottom plate 20 as more clearly shown in Figs. 3 and 5.

20 The side plates 10 and the end plates 11 and 12 are formed of metal plate and the side plates 10 are preferably reinforced by externally disposed channel bars 27.

The end plate 11 at the forward end of 25 the machine is provided with a plurality of relatively narrow horizontal slots 28 arranged one above another and adapted to permit sheets of water to be discharged from the pressure box into the grader.

30 The end plate 11 is also provided opposite the lowermost compartment of the pressure box with a slot 30 that is preferably larger than the slots 28 so that a somewhat stronger current of water may be created in the lower 35 portion of the grader box adjacent to the inlet end.

The lower compartment of the pressure box is connected by a flexible pipe or hose 31 with a pressure tank 32 which is supported by a stem 33 that telescopes into a base member 34 in such a manner that the height of the pressure tank 32 may be adjusted to vary the pressure within the lower compartment of the pressure box. Water 45 may be supplied to the tank 32 through a hose 35.

Material that is to be graded as sand, gravel, ores, or the like, may be delivered from a chute 36 into a receptacle or box 37 that is supported on the frame 13 above the inlet end of the machine. The box 37 is divided into two compartments 38 and 39 by a partition wall 40 which is preferably cut away as shown at 41 in Fig. 2 to permit water with which the material is washed down the chute 36 to pass from the compartment 38 into the compartment 39. The box 37 is provided on one side with two discharge openings 41 and 42 that communicate with the compartments 38 and 39 respectively and that each have sliding doors or gates 43 associated therewith by which such discharge openings 41 or 42 may be partially or entirely closed.

65 Mounted on suitable bearings 44 between

the bottom of the box 37 and the top of the grader box is a shaft 45 upon which two overshot wheels 46 and 47 are secured.

The wheel 47 is arranged to receive water that issues from the opening 42 and to discharge such water directly into the top of the pressure box 14 while the wheel 46 is arranged to receive material and a small amount of water that issues from the opening 41 and to discharge such material and water onto an inclined plate 48 by which the said material is directed through an opening 50 into the upper end of the grader box. The compartments or buckets of the wheel 46 are preferably shaped substantially as shown in Fig. 7 so that they will distribute the material evenly across the plate 48 from which such material will slide in an evenly distributed sheet into the water of the grader box.

85 A baffle plate 51 is provided opposite the opening 50 to direct the discharging material downwardly, such baffle plate being adjustably supported by rods or bolts 52 that extend upwardly through slots 53 in brackets 54.

90 The grader box is provided at its outlet end adjacent said upper edge thereof with a discharge opening 55 that communicates with the interior of a rotary screen 56 through which all water that is discharged from the grader box must pass. The screen 56 is mounted on a horizontal shaft 57 that is provided with a gear wheel 58 that meshes with another gear wheel 59 on the shaft 45 100 so that the screen 56 will be constantly rotated by power derived from water and material that are delivered onto the overshot wheels 46 and 47.

105 The screen 56 is of very fine mesh and prevents the discharge of silt and mud there-through so that the water that issues from the outlet 55 will be relieved of all solid matter that would tend to settle and may safely be discharged into an ordinary sewer or if desired may be pumped to a higher elevation and again used for washing material down the chute 36.

110 The rotation of the screen 56 keeps it clean at all times and prevents it from clogging as a stationary screen would do.

115 The grader box is provided at the discharge end and adjacent the bottom thereof with a hopper shaped receptacle 60 that serves to catch the finer silt and clay that settles at the discharge end of the box and the receptacle 60 is tapped by a pipe 61 having a suitable valve 62 which may be opened at intervals to draw off or permit the discharge of the settling.

120 The valve openings 21 which are arranged at regular intervals along the bottom of the grader box are adapted to be closed by spherical valve members or balls 63 that are secured on stems 64 that project downwardly 130

through the openings 21. The stems 64 are pivotally secured to transverse arms 65 that are each pivotally connected at one end with a downwardly projecting rigid stem 66 and 5 that are each provided at the other end with a flattened portion 67 arranged to be engaged by a cam 68 on a shaft 70. The cams 68 are distributed around the shaft 70 so that some of such cams will be operating 10 at all times thereby keeping a fairly constant torsion on the shaft 70.

By the above described arrangement it will be seen that each of the spherical valve members 63 will be lifted from its seat once 15 at each complete revolution of the shaft 70 and will thereby permit the discharge of material that has collected around such valve member.

The material will settle in such a manner 20 as to form a cone-shaped receptacle around each of the valve members 63 and at each opening of a valve member a small amount of the material that has collected around the sides thereof will be discharged but the 25 valve member will not remain open long enough to permit the discharge of any considerable amount of water.

The use of a spherical valve disposed within the grader box and arranged to be lifted off its seat overcomes the very grave difficulty of sliding valves with their consequent excessive wear and friction where they are subjected to the action of sand and where lubrication is not possible.

25 The shaft 70 may be provided at the forward end of the machine with a belt pulley 71 that is connected by a belt 72 with another belt pulley 73 on the shaft 45 so that the shaft 70 will be driven whenever material is being delivered to the grader box.

A discharge trough or flume 74 is preferably disposed lengthwise of the machine below the valve openings 21 and is inclined downwardly from the head toward the discharge end of the machine so that material that drops into such trough will be washed toward and discharged from the lower end thereof.

In addition to the trough 74 I have provided another receptacle or trough 75 disposed at one side of the center of the machine and arranged to receive material from relatively short inclined troughs 76, one of which may be supported below each of the discharge openings 21.

When the machine is used for washing and grading sand a number of the troughs 76 at the inlet end of the machine will preferably be removed as shown in Fig. 1 thereby allowing the washed and graded sand from a number of the valve openings 21 at the head end of the machine to discharge directly into the inclined trough 74. Sufficient water will be discharged with the sand 65 to cause such sand to be washed down the

inclined trough 74 and discharged from the lower end thereof. The finer sand, clay, etc., will be discharged from the valve openings near the lower end of the machine into the inclined transverse troughs 76 and will be 70 delivered into the trough or receptacle 75.

A different grade of sand will be delivered from each of the valve openings 21 and if it is desired to preserve these different grades separately transverse inclined troughs 76 75 may be arranged below each valve opening and may be made to deliver into separate receptacles. In the washing and grading of sand for ordinary commercial purposes, it will not be necessary to preserve these 80 various grades separately, hence all of the grades that are suitable for commercial use will be allowed to discharge into the trough 74 while the finer sand will be conducted by the troughs 76 into the receptacle 75. 85

When the sand is graded by screening it is graded with respect to size only but when it is graded by the hydraulic process herein described it is graded with respect to size and also with respect to the specific gravity 90 of the particles, the particles of lighter material being ordinarily carried over and discharged with the refuse.

In preparing sand for commercial use it has also been found desirable to wash such sand thoroughly to remove organic matter which is ordinarily found therein. This machine affects a thorough washing of the sand at the same time the sand is being graded thereby removing all organic matter. The 100 water that is introduced into the lower compartment of the pressure tank 14 is always fresh, clean water and it is through this strata of fresh, clean water that the sand must settle just prior to its being discharged 105 from the machine.

The water that issues from the outlet 55 after passing through the screen 56 is practically free from solid matter and may be discharged into a conduit 77 which may 110 conduct such water to a suitable pump, not shown, by which it may be elevated and again permitted to wash down the flume 36 with material that is being delivered into such flume. If the supply of water at a 115 higher elevation than the machine is plentiful the water obviously will not be used the second time.

If desired, an overshot wheel similar to the wheel 47 may be mounted at the outlet end 120 of the machine in such a manner that the discharge water will pass thereover and the power generated by such wheel may be used to assist in rotating the screen 57 and operating the valves 63. 125

This apparatus is adapted for washing and grading any material that is heavier than water and while it has been referred to as particularly advantageous for washing and grading sand for commercial purposes it 130

will be understood that it is equally well adapted for grading and separating ores, which ores are graded according to their specific gravity.

5. When the machine is used for grading and separating ores a riffle 78 is placed just below the slot 30 and above the valve 63 next adjacent the inlet end of the machine, which riffle serves to direct the heavier materials toward the inlet end of the machine so that such heavier materials will be discharged from the first valve opening 21.

When the machine is used for classifying ores, I also provide on the end wall 12 at the 15 discharge end of the machine a plurality of transverse shelves 80 upon which different grades of very fine material will tend to settle.

In addition to washing and grading sand 20 and separating ores this machine is useful for other purposes, as for instance, it may be used for grading grains where it is not a disadvantage to have such grains subjected to the action of water.

25. From the foregoing description taken in connection with the accompanying drawings the advantages of the construction and method of operation of this apparatus will be readily apparent, but while I have described the principle of operation of the 30 invention together with the device which I now consider to be the best embodiment thereof it will be understood that the structure shown is merely illustrative and that 35 such changes may be made as are within the scope of the following claims.

What I claim is:

1. Apparatus of the class described comprising a grader box, a pressure tank at one 40 end of said grader box, a perforated wall separating said grader box from said pressure tank, a partition wall dividing said pressure tank into an upper and a lower compartment, means for delivering water 45 into said upper compartment and separate means for delivering water at higher pressure to said lower compartment.

2. Apparatus of the class described comprising a V-shaped grader box, a pressure 50 tank at one end of said grader box, a wall separating said pressure tank from said grader box said wall having a plurality of horizontal slots arranged one above another, a partition wall dividing said pressure tank 55 into an upper and a lower compartment, means for delivering water to said upper compartment, and separate means for delivering clean water at a higher pressure to said lower compartment.

60. 3. Apparatus of the class described comprising a grader box, a pressure tank at one

end of said grader box, a wall separating said pressure tank and said grader box, said wall having transverse slots spaced one above another, a partition dividing said 65 pressure tank into an upper and a lower compartment, a valve in said partition for controlling the flow of water therethrough, means for delivering water to said upper compartment and a vertically adjustable water supply tank connected with said lower compartment whereby the pressure of the water delivered to said lower compartment may be varied.

4. Apparatus of the class described comprising a grader box, a pressure tank at one 75 end of said grader box, a wall separating said pressure tank from said grader box, said wall having a plurality of horizontal slots arranged one above another, a partition dividing said pressure tank into an upper and a lower compartment, a material receptacle arranged above said pressure tank and divided into two compartments by a partition wall that is cut away to permit the 80 overflow of water from one to the other of said compartments, means for permitting the discharge of said overflow water into the upper end of said pressure tank, a vertically adjustable fresh water tank and means 85 for delivering water from said fresh water tank into the lower compartment of said pressure tank.

5. A grading and washing machine comprising a V-shaped grader box, a pressure 95 tank at one end of said grader box and communicating with said grader box by a plurality of horizontal slots arranged one above another, an inclined plate at the top of said tank and arranged to deliver into said 100 grader box, a baffle plate supported for vertical and horizontal adjustment in front of the location at which said inclined plate delivers, overshot bucket wheels arranged above said pressure tank and said inclined plate respectively, a material receptacle arranged above said overshot bucket wheels and divided into two compartments by a partition wall that is cut away to permit 105 water to overflow from one to the other of said compartments, means for delivering material and water into one of said compartments, means for discharging said material and a portion of the water onto the overshot wheel above said inclined plate and means for discharging overflow water from the other compartment onto said overshot 110 wheel that delivers into said pressure tank.

Signed at Seattle, Washington, this 1st day of February, 1920.

EUGENE D. MERWIN.
